UNITED STATES PATENT OFFICE.

JOHN FRANCIS MURPHY, OF LOUISVILLE, KENTUCKY.

TABLE-LEG CONSTRUCTION.

Application filed March 2, 1925. Serial No. 12,718.

This invention relates to a novel and practical construction for table legs of the type adapted to be collapsed inwardly toward the underside of the table to permit the latter to be conveniently stored or handled.

Small tables of the type of card tables, sewing tables and the like are usually equipped with folding or collapsible legs which permit of the table being made into a flat condition, thereby to occupy a minimum space and also to facilitate carrying or shipping. However, due to the relatively light construction usually employed, such tables are unstable, and in spite of the assistance of bracing means usually lack rigidity, strength and stability especially in the supporting means.

Accordingly, the present invention has primarily in view the provision of a novel tensioned leg construction which requires no independent bracing means, and which when set up for use provides a rigid and firm support for the table top and yet on the other hand may be readily and quickly collapsed when it is desired to either transport or store the table.

A further object of the invention is to provide simple and practical hinging means for the leg so that the same may be readily assembled and economically manufactured.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings in which—

Figure 1 is an elevation looking at one corner of a table equipped with the present novel leg construction.

Figure 2 is a vertical sectional view taken on the line 2—2 of Fig. 1.

Figure 3 is a view similar to Fig. 2 illustrating the construction partially collapsed.

Figure 4 is a bottom plan view of a corner of a table showing the mounting for the novel leg construction.

Figure 5 is a cross-sectional view taken on the line 5—5 of Fig. 4.

Figure 6 is a detail sectional view taken on the line 6—6 of Fig. 4.

Figure 7 is a detail cross-sectional view taken on the line 7—7 of Figure 1.

Like reference characters designate corresponding parts throughout the several figures of the drawings.

In carrying the present invention into effect it is proposed to utilize the novel leg construction in connection with a table top T of any desired dimensions and shape, the same being supported by the novel legs L preferably located at the corners thereof and adapted to fold inwardly toward the back of the table top T.

Referring to the said legs L it will be observed that the same are preferably made from a single piece of strong resilient wood such as hickory, oak or the like, or if desired metal could be used. However, due to lightness, wood is preferably employed and in the embodiment shown a piece of resilient wood is preferably kerfed or cut to provide the spaced yielding outside hinge sections 1 and 2 and an intermediate locking section 3, the upper ends of said hinge members 1 and 2 preferably being notched on opposite sides thereby to be held against a main hinge pin 5 by a special spring clamp S and said hinge pin extending diagonally between the frame members 6 and 6^a of the table as will be observed from Fig. 4.

The spring clamp S serves two functions, namely, that of holding the members 1 and 2 to the pin 5 and also spreading the same apart to place the same in tension. As clearly shown in Fig. 5 the clamp or clip preferably consists of a looped body portion 7 having the angular spring arms 8 which terminate in loops 9 that fit over the hinge pin 5, the resilient angular arms 8 serving to clamp the ends of the hinge member 1 to the bar in a practical manner. This makes the arms 1 easy to assemble on the hinge pin 5 although it will of course be understood that the spring clasp or clamp S is only one means of attaining that end.

Spaced from the main hinge pin, and nearer the corner angle of the frame members 6 and 6^a there is also arranged an anchoring pin or bar 10. This bar preferably has pivotally mounted thereon a guide sleeve 11 in which the locking member 3 of the leg slides. As will be observed from Figs. 2 and 3 the said sleeve 11 is a hollow tubular member having the perforated ears 12 for receiving the pin 10 so that it is free to rotate thereon. Also it will be observed that the locking member 3 is provided with a keeper notch 13 for receiving the bar 10.

thereby to hold the leg in its locked vertical position as shown in Fig. 2. When it is desired to collapse the leg it is simply necessary to give the same a sharp blow sufficient 5 to cause the notch 13 to move out of registry with the bar 10, as shown in Fig. 3, and then the leg may be collapsed into the position shown in Figs. 4 and 6, the upper end of the locking member sliding in the sleeve 11 to 10 the position shown in the last named figure.

It will be observed that the main hinge pin 5 and the anchor pin or bar 10 are spaced apart but in the same horizontal plane, whereby when the leg member is 15 shifted to a vertical position or a position at right angles to a plane intersecting both the hinge pin 5 and the pin or bar 11, the locking section 3 is placed under tension and when the notch 13 reaches the bar the entire 20 leg construction is locked under tension. Also, it is pointed out that the spring clip S serves to maintain the hinge sections 1 and 2 spaced apart at their upper end thereby to also place these members under 25 tension so that they may effectually resist lateral thrusts or side strains. Thus, when the leg members are in the position of use they form in effect a tensioned tripod which is able to withstand pressure or weight imposed 30 on the top of the table either from the direction of a corner or sidewise. When all of the leg units are set up in usable position it will be apparent that they all materially contribute to a rigid and substantial 35 support for the table top.

In the embodiment shown, where the legs are preferably made of resilient wood it is preferable to place a reinforcing band 14 where the sections 1, 2 and 3 terminate so as 40 to prevent the foot portion 15 of the leg from becoming split due to the tension under which the parts 1, 2 and 3 are placed when set up for use. As previously indicated, metal may be used as readily as wood but 45 because of its lightness the latter is preferred. A distinctive feature of the present invention, however, is a tensioned collapsible table leg construction which is automatically braced against strains and loading 50 stresses by the mere act of setting it up for use.

In making the legs L, it may be observed that before the same is split into the sections 1, 2 and 3 it is preferably notched on 55 both sides near the ends, thereby to provide the notches for receiving the spring arms 8 of the clip as well as the hinge pin 5, while in connection with the locking section 3 the notch at one side thereof forms the keeper notch 13. Of course, when the leg is set up for use only one of the notches in the member 3 is used as indicated at 13. Of course, when the leg is set up for use only 60 one of the notches in the member 3 is used as indicated at 13, but in the course of manu-

facture, it is more convenient and cheaper to notch both sides rather than to notch one section on one side and the other two sections on the other. Furthermore, there is an additional advantage in thus forming the 70 legs because it makes them readily reversible whereby they may be turned around or turned over. For instance, if the leg was left standing for a great length of time and the wood should lose some of its resiliency, 75 the leg could be restored to its original strength and springiness by slipping the same out from beneath the spring arms 8 of the clip and turning it over and attaching it in the new position. 80

Also in connection with the hinge pin 5 and locking bar 10 it may be pointed out that the same may be readily set at different angles with reference to the frame bars 6 and 6'. When the legs are used on a square 85 table it is preferred not to set them at exactly a 90° angle to the axis of the table, thereby to avoid overlapping and stacking of the legs when in collapsed condition. Therefore, when the legs are used on a 90 square table it is preferred to set the pins 5 and 10 at an angle indicated by the dot-and-dash line x—x and y—y in Figure 4. It will of course be understood that the angular setting of the pins 5 and 10 will be governed 95 entirely by the shape of the table, the arrangement in each instance being intended to avoid overlapping or piling up of the legs when collapsed for storage or carrying. 100

Without further description it is thought that the features and advantages of the invention will be readily apparent to those skilled in the art, and it will of course be understood that changes in the form, proportion and minor details of construction may be resorted to without departing from the spirit of the invention and scope of the appended claims. 105

I claim:—

1. An individual folding leg construction 11 for table tops including a hinge pin and an anchor member arranged in spaced relation at the underside of the said top, the anchor member being located between the hinge pin and a corner of the table top, and said individual leg including spaced sections connected to said hinge pin, and an intermediate locking and tensioning section adapted to engage with said anchor member. 115

2. A folding table leg construction including a hinge pin and an anchor bar arranged in spaced relation, and a table leg proper comprising a pair of hinge sections connected to said hinge pin, a guide sleeve carried by said anchor bar, and an intermediate locking section slidably fitting in said guide sleeve and adapted to have a locking engagement with the anchor bar. 120

3. A folding table leg construction comprising a leg support carried by the table 125

top, a leg member proper having three yielding sections, two of which are pivotally mounted on said support, an anchor member for the third section, and means for guiding said third section to said anchor member.

4. A tensioned table leg construction comprising a leg member proper having three yielding sections, means for pivotally mounting two of said sections on a common axis, means for maintaining said latter sections in spaced tensioned relation, and means for holding and guiding the third one of said sections to an anchor point spaced from said axis and also in a position lying at right angles to a plane intersecting said axis and anchor point.

5. A folding table leg construction comprising a pair of aligned pin members and a table leg proper consisting of three resilient sections united by a common foot portion, means for pivotally mounting two of said sections on one of said pins, and means for automatically guiding the third one of said sections into engagement with the other of said pins as the leg is moved from a plane parallel with the said aligned pins to a position at right angles thereto.

6. A folding table leg construction comprising a hinge pin and an anchor bar arranged in spaced relation, and a leg member proper comprising a pair of outer sections and an intermediate section united by a common foot portion, means for pivotally connecting said outer sections to the hinge pin, and means carried by the anchor bar for guiding said intermediate section into locked engagement with the bar.

7. A folding table leg construction comprising a hinge pin and an anchor bar arranged in spaced relation, and a leg member proper comprising a pair of outer sections and an intermediate section united at a common foot portion, means for pivotally connecting said outer sections to the hinge pin and also holding the same in spaced apart

tensioned relation, and a sleeve pivotally carried by said anchor pin and receiving the intermediate section, said latter section being provided with a keeper notch for engaging with the anchor pin.

8. A folding table leg construction comprising a hinge pin and an anchor bar arranged in spaced relation, and a leg member proper comprising a pair of outer sections and an intermediate section united by a common foot portion, a spring clip for holding said outer sections pivotally connected to the hinge pin and also maintaining the same in spread-apart tensioned relation, and a tubular sleeve pivotally mounted on the anchor bar, and the intermediate section being provided with a notch and slidably fitting in said sleeve whereby the notch will engage with the bar when the leg member is shifted to a plane at right angles to a plane intersecting the pin and hinge pin.

9. A folding table leg construction including spaced apart pin elements and a table leg proper consisting of three resilient sections united by a common foot portion, means for pivotally uniting two of said sections to one of said pin elements, and means for guiding the other of said sections into engagement with the other pin element thereby to provide a tensioned tripod relationship between said sections.

10. An individual folding leg construction for table tops comprising a leg supporting member spaced from one corner of the table, and said leg proper comprising members pivotally connected to said supporting member and a locking and tensioning member, and means located at the underside of said table top between said supporting member and the corner of the table for releasably engaging and holding said locking and tensioning member.

In testimony whereof I hereunto affix my signature.

JOHN FRANCIS MURPHY.
